FIG. 1 is a top plan view of a portable sewing machine housing showing my new design;

FIG. 2 is a head end view thereof;

FIG. 3 is a front elevational view;

FIG. 4 is a standard end view;

FIG. 5 is a rear elevational view;

FIG. 6 is a head end view of the jacket removed from the sewing machine housing;

FIG. 7 is a bottom plan view thereof;

FIG. 8 is a front elevational view;

FIG. 9 is a standard end view;

FIG. 10 is a rear elevational view;

FIG. 11 is a top plan view;

FIG. 12 is a head end view of the sewing machine housing with the jacket removed;

FIG. 13 is a front elevational view thereof;

FIG. 14 is a standard end view;

FIG. 15 is a rear elevational view;

FIG. 16 is a top plan view; and

FIG. 17 is a bottom plan view.

I claim:

The ornamental design for a portable sewing machine, as shown.
